THERMOCOUPLE TUBE

John E. Buell, Birmingham, Ala.

Application October 12, 1937, Serial No. 168,680

2 Claims. (Cl. 136—4)

This invention relates to improved means for supporting thermo-couples in such a way as to exclude air from the tube normally used to surround the thermo-couple. The thermo-couple and its protective tube are of conventional form and the invention is particularly directed to means combined therewith for excluding air from the conventional protective tube. The novel means includes an extension pipe formed of common relatively inexpensive metal carrying a stopper on its end remote from the thermo-couple, which is adapted to be compressed so as to adequately exclude air, which would tend to oxidize the active elements of the thermo-couple. It is important to use an extension tube of considerable length because the compressible or resilient materials of which the stoppers are made would normally be melted or destroyed by the prevailing temperatures maintained in the immediate zone of the thermo-couple.

The above and more detailed features of the invention will be readily apparent from the following detailed disclosure when read in connection with the accompanying drawing.

25 In the drawing—

Fig. 1 is a small scale view of a furnace equipped with a thermo-couple and the extension and sealing means of the present invention; Fig. 2 is an enlarged longitudinal section through a thermo-couple equipped with the extension pipe and air-excluding tube and related parts embodying the present invention; Fig. 3 is a horizontal section on line 3—3 of Fig. 2.

Referring in detail to the drawing, 10 is a conventional type of thermo-couple including elements 11 and 12 of dissimilar metals, these being covered with suitable porcelain insulators 13. The extreme end of the thermo-couple extends into a porcelain cup 14 of conventional form, which rests on the closed end 15 of a tube 16, which is formed of a metal, such as chrome iron characterized by a high resistance to the corrosive action of furnace gases.

As ordinarily constructed heretofore insofar as I am aware, there has been no provision of means to prevent the entrance of air to the interior of the protective tube 16. This has resulted in the early destruction of the thermo-couple due to the oxidizing action of the air on the highly heated metallic elements of such thermo-couple. The present invention aims to lengthen the life of the thermo-couple and one feature which contributes to this lengthened life is the means to be presently described for excluding air from the tube 16.

In accordance with the present invention, I secure a coupling 17 to the upper end of the tube 16, this coupling being carried by an extension pipe 18 formed of common and relatively inexpensive metal, such as steel, ordinary steel tubing or pipe being suitable for the purpose. It is desirable that the pipe 18 be of considerable length, so as to position an air excluding stopper 19 a considerable distance from the heated zone 20 of the furnace 21, in which the thermo-couple may be installed. The stopper 19 will preferably be of yieldable material such as rubber or the like, so that it can be forcibly compressed into engagement with the inner surfaces of the pipe 18 and thus form an approximately air-tight or hermetic seal. Rubber is a suitable material for the stopper and when rubber or like material is used it is important that the pipe 18 be of such length that the stopper will be located far enough away from the furnace to prevent its being melted. Engaging the top surface of the stopper, there is a fibre disc 22, which is adapted to coat with the stopper and with a cap 23, which has a screw threaded engagement with the threaded end 24 of the pipe.

As thus arranged, it is clear that by screwing down the cap the fibre disc will cause the material of the stopper to yield or be compressed so as to bring about the hermetic or air excluding seal in the end of the pipe. The rubber stopper may also serve as a means for sustaining the thermo-couple element 10 and the insulators. As shown, there are a pair of uppermost insulators 25 and 26, surrounding the terminals 27 and 28. Engaging these insulators, there is a composition base 29 carrying metal connectors 30 and 31, to which lead wires 32 and 33 are secured, which lead to the pyrometer 34. With the arrangement described, it will be apparent that only a short length of the relatively expensive chrome iron pipe 18 is needed, this being a part of the device which extends through the brickwork and is exposed to the direct action of the furnace gases. The long length of pipe 18, which serves to position the stopper 19 a safe distance away from the heat of the furnace, is of relatively less expensive steel or iron. While the tube 16 and pipe 18 are shown as being connected by a screw threaded coupling, a non-threaded connection can also be used and in some cases the coupling sleeve may be joined to the pipe and tube also by a welded body of metal, as indicated at 35 and 36.

It is also within the scope of my invention to omit the coupling 17 and extension pipe 18 and

to merely lengthen the tube 16 sufficiently to position the stopper 19 far enough away from the intense heat to prevent its destruction.

The thermo-couple protective device described can be easily and quickly manufactured at a relatively low cost from stock materials and it effects important economies in various industrial establishments by prolonging the life of the thermo-couples.

10 While I have described quite precisely the details of construction of the embodiment of the invention herein illustrated it is to be understood that various modifications and substitutions may be made by those skilled in the art 15 without departure from the invention as defined in the appended claims.

What I claim is:

1. In combination, a thermo-couple junction housed in a tube closed at one end and open at 20 the other, said tube being of chrome iron characterized by a high resistance to the destructive action of furnace gases, the closed end being adapted to extend into a furnace, an extension pipe, a screw coupling uniting the open end of 25 the tube to said pipe, a stopper of resilient material subject to deterioration by heat and furnace gases compressively assembled in the end of the pipe remote from the coupling, a fiber disk engaging the top of said stopper and a cap

screwed on said remote end of the pipe and co-acting with the disk to force it into compressive relation with the stopper so as to cause a portion thereof to overlap said remote end of the pipe to hermetically seal the assemblage and thus 5 prevent the destructive oxidation of said thermo-couple element, said junction having leads extending through both the stopper and the disk.

2. In combination, a thermo-couple junction enclosed in a tube closed at one end and open 10 at the other, said tube being of metal characterized by high resistance to the destructive action of furnace gases, the closed end thereof being adapted to extend into a furnace, an extension pipe, a coupling uniting the open end of the tube 15 to said pipe, a stopper of resilient material subject to deterioration by heat and furnace gases compressively assembled in the end of the pipe remote from said coupling, a disk of insulating material engaging the top of said stopper, a cap 20 screwed on said remote end of the pipe coacting with the disk to force it into compressive relation with the stopper so as to cause a portion thereof to overlap said end of the pipe to hermetically seal the assemblage and thus prevent 25 the destructive oxidation of said thermo-couple element, said junction having leads extending through both the stopper and the disc.

JOHN E. BUELL.
